UNITED STATES PATENT OFFICE.

AARON JOHNSON, OF CORNING, MISSOURI.

STREAM-BED-DIGGING DEVICE.

Application filed July 9, 1924. Serial No. 724,988.

To all whom it may concern:

Be it known that I, AARON JOHNSON, a citizen of the United States, residing at Corning, in the county of Holt, State of Missouri, have invented a new and useful Stream-Bed-Digging Device; and I do hereby declare the following to be a full, clear, and exact description of the invention, such as will enable others skilled in the art to 10 which it appertains to make and use the same.

The invention relates to digging and ditching devices for stream beds and has for its object to provide a device of this character, which is particularly adapted for use 15 in small streams where sand bars form rapidly, and one with which the channel of the stream may be maintained open, easily and at a minimum cost, and by maintaining the stream or channel open erosion of 20 the banks will be obviated.

A further object is to provide a channel digging machine comprising a downwardly and forwardly inclined pivoted frame carried by a boat, which frame is pivotally 25 mounted on a transversely disposed driven shaft, a transversely disposed crank shaft carried by the free end of the frame and driven by chain and sprocket connections with the first mentioned shaft, and to provide 30 a plurality of digging elements carried by the cranks of the crank shaft and having their rear ends provided with a yoke slidably mounted and guided on the driven shaft.

Also to provide positive driving means for 35 the opposite ends of the driven shaft, and the crank shaft whereby during the digging operation the crank shaft and driven shaft will be positively driven and relieved from twisting strain incident to the intermittent 40 digging and raising of the digging elements.

A further object is to provide adjacent opposite sides of the boat windlass drums which rotate together and have cable connections with the free end of the pivoted 45 frame and form means whereby said frame may be elevated or lowered to various positions with the weight thereof supported by the cables at opposite corners thereof for preventing a twisting action on the frame 50 and binding or misalignment of the shaft.

With the above and other objects in view the invention resides in the combination and arrangement of parts as hereinafter set forth, shown in the drawing, described and 55 claimed, it being understood that changes in the precise embodiment of the invention

may be made within the scope of what is claimed without departing from the spirit of the invention.

In the drawing:

Figure 1 is a side elevation of the dredging and ditching machine.

Figure 2 is a top plan view of the machine.

Figure 3 is a front elevation of the machine showing a vertical transverse sectional view through a stream bed.

Figure 4 is a perspective view of one of the digging elements.

Referring to the drawing, the numeral 1 designates the hull of the boat which may be of any desired type, and may be propelled in any suitable manner, however it is preferably of the barge or scow type shown which draws the minimum amount of water.

Extending upwardly from the hull 1 adjacent the forward end thereof are bearing members 2, in which bearing members is rotatably mounted a transversely disposed driven shaft 3, on which shaft is pivotally mounted the side bars 4 of a downwardly and forwardly extending digger carrying frame 5. Bars 4 are braced in relation to each other and held in spaced parallel relation by transversely disposed bars 6, therefore it will be seen that the frame 5 is a rigid one.

By pivotally mounting the frame 5 on the transversely disposed shaft 3, it will be seen that the frame as a whole may be raised or lowered at its free end by the cables 7, which are connected to the outer ends of the bars 4 and extend upwardly over pulleys 8 carried by pivoted masts 9, and which cables extend downwardly around drums 10 mounted on the deck of the hull 1, in a manner whereby when the drums 10, which are secured on the rotatable shaft 11 are rotated, equal strains will be imparted on the cables 7, consequently the frame 5 will not have a twisting action diagonally which will cause the same to bind on the driven shaft 3. The shaft 11 has its opposite ends provided with cranks 12, therefore it will be seen that the operator may adjust the free end of the frame at various distances from the bottom 13 of the stream 14.

Rotatably mounted in the forward ends of the side bars 4 of the frame is a transversely disposed crank shaft 15, which crank shaft is provided with a plurality of cranks 16 extending in opposite directions and in

the same plane, and pivotally connected to said cranks 16 by means of bearing members 17 are digger bars 18, the free ends of which are intermittently forced downwardly and raised during a digging operation in the bottom of a stream as clearly shown in Figure 1. By providing a plurality of cranks 16, extending in opposite directions, it will be seen that during the rotation of the crank 10 shaft 15 a digging action will take place at all times, and the ground piercing elements 19 carried by the digging members 18 will dig into the ground and loosen the same in a manner whereby it may be re- 15 moved in any suitable manner or allowed to drift off incident to the current in the stream, which is particularly true where sand bars form in the stream and change the course of the current thereof.

Secured to the upper sides of the rear ends of the digger bars 18 are inverted U-shaped members 20, which members arch the transversely disposed shaft 3, and guide the rear end of the bars 18 on the shafts 25 during the rotation and reciprocation thereof, and maintain the rear ends of the bars at substantially the same elevation during the digging operation, and it will be seen by the sliding connection of the bars 18 with the shaft 3 that during the rotation of the cranks 16, not only downward digging action is imparted on the members 19, but during the rearward movement thereof a slight prying action takes place, thereby 35 dislodging and breaking material on the bottom of the stream. Crank shaft 15 is positively driven at both ends thereof by means of sprocket chains 21 at opposite sides of the frame 5, which sprocket chains 40 extend over sprockets 22 carried by the ends of the crank shaft 15 and over sprockets 23 carried by the ends of the rotatable shaft 3, therefore it will be seen that a twisting strain will not take place on the frame as 45 the strain is equally distributed at opposite sides thereof through the sprocket chain drive connection, consequently binding of any of the parts which are pivotally or slidably mounted on the shaft 3 will be ob- 50 viated. Mounted on the hull 1 is a conventional form of engine 24, which engine may be a gas engine if desired and rotates a transversely disposed drive shaft 25. The ends of the drive shaft 25 are provided with sprockets 26, which sprockets have extending thereover sprocket chains 27 which also extend over sprockets 28 carried by the ends of the shaft 3, therefore it will be seen that the shaft 3 is positively driven at both ends thereof. Pivoted masts 9 are pivotally connected at 29 to the hull of the boat and are provided with removable braces 30, which braces normally maintain the masts 9 in vertical positions, but at the same time when 65 removed allow the masts to be folded onto

the hull so that the digging device may be moved under bridges and the like.

From the above it will be seen that a digging and dredging machine is provided which is particularly adapted for use in small streams and one wherein an intermittent digging and prying action will take place. It will also be seen that power is transmitted over the pivoted frame to the digging elements in a manner whereby the strain is equally distributed over the frame, and also in a manner whereby the power connections will not interfere with the pivotal movement of the frame in adjusting the same to various elevations in relation to the bottom of a stream.

The invention having been set forth what is claimed as new and useful is:—

1. A river bottom excavating machine comprising a hull, a straight transversely disposed shaft rotatably mounted in bearings adjacent one end of the hull, means for rotating said shaft, said means driving the shaft from opposite ends thereof, a frame pivotally mounted on said transversely disposed shaft and extending downwardly, a crank shaft carried by the free end of the frame, driving connections between the crank shaft and the first mentioned shaft adjacent the opposite sides of the frame, a plurality of bars carried by said crank shaft, digging elements carried by the lower ends of said bars, the rear ends of said bars being provided with yokes arching the straight transversely disposed shaft and having a slidable connection on said shaft and means for raising and lowering said pivoted frame at its free end.

2. A river bottom excavating machine comprising a hull, a straight transversely disposed shaft carried by said hull, means for driving said shaft at the ends thereof, a frame pivotally mounted on said shaft, a crank shaft carried by the free end of the frame, digging elements carried by the cranks of the crank shaft, said digging elements being provided with slidable connections with the straight transversely disposed shaft, driving connections between the transversely disposed shaft and the crank shaft at opposite sides of the frame, cables connected to the opposite sides of the frame adjacent its free end and means for simultaneously imparting pulls on said cables for raising and lowering the free end of the frame and preventing a twisting strain on the straight transversely disposed shaft and crank shaft.

3. A river bottom excavating machine comprising a hull, a straight transversely disposed rotatable drive shaft carried adjacent one end of said hull, a frame pivotally mounted on said drive shaft, a crank shaft carried by the free end of said frame, sprocket and chain driving connections be-

tween the straight transversely disposed shaft and the crank shaft and disposed at opposite sides of the frame, bars pivotally mounted on the crank shaft, said bars being pivotally and slidably connected to the straight transversely disposed shaft at their rear ends, said pivotal and slidable connections forming means whereby during the rotation of the crank shaft a prying action

will be imparted on digger elements carried 10 by the digger bars.

In testimony whereof I have signed my name to this specification in the presence of two subscribing witnesses.

AARON JOHNSON.
